United States Patent

Des. 237,547
Patented Nov. 4, 1975

237,547

DIALYSER CORE

Romano Flandoli, Mirandola, Italy, assignor to
Sandoz Ltd., Basel, Switzerland

Filed June 7, 1973, Ser. No. 367,970

Term of patent 14 years

Int. Cl. D24—02

U.S. Cl. D83—1 F

FIG. 4.

FIG. 1 is a top perspective view of a dialyser core; showing my new design;

FIG. 2 is a bottom perspective view thereof;

FIG. 3 is an end elevational view thereof; and

FIG. 4 is an exploded perspective view showing the base section and the cover section thereof disassembled.

I claim:

The ornamental design for a dialyser core, as shown.
